UNITED STATES PATENT OFFICE.

ADRIAN R. ROGERS, OF DU BOIS, PENNSYLVANIA, ASSIGNOR TO GEORGE ALLSOP,
JAMES A. FYE, AND GEORGE STRONG, OF DU BOIS, PENNSYLVANIA, AND WILLIAM
STRONG, OF BROOKVILLE BOROUGH, PENNSYLVANIA.

METALLIC RAILWAY TIE.

Application filed February 26, 1927. Serial No. 171,266.

Broadly this invention relates to ties used in the construction of railways, but it more especially comprehends the type of tie employed in the construction of mine railways and general construction work.

One object of this invention is the provision of a steel or metal tie for supporting the rails of railways, constructed to permit ready positioning and securing of the rails thereon and their expeditious removal when desired.

An important object of this invention is the provision of a metal hollow tie of the above character having fixed and movable means for securing the rails thereon, said means being readily adjustable to accommodate rails of varying sizes and weights, within predetermined limits.

A further object of this invention is the provision of a metal tie of this character having a portion of its surface adjacent the inner sides of the opposing rails struck up to form an integral strap or loop to receive a slidable rail-flange engageable wedge clip, which is adjustable to different sized rails, and having means associated with the struck up portion and clip to lock the latter in the desired adjusted position.

With these and other objects in view, which will become apparent at the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a top plan view of my improved tie with parts operatively positioned and broken away intermediate the rails;

Fig. 2 is a longitudinal sectional view taken on the line 2—2 of Fig. 1; and

Fig. 3 is a cross sectional view taken on the line 3—3 of Fig. 1.

The types of metal ties now in use with which I am familiar have proven either too costly to manufacture or by not being adjustable to different sized rails and for other reasons unsatisfactory, and it was to overcome such deficiencies, and to provide a metallic tie manufacturable at a minimum cost, having fixed and movable rail-flange engageable clips, the movable clips being slidable at right angles to the rails into and out of

engagement with the rail flange, and adjustable to different sized rails, and having means to prevent their vertical or lateral movement when locked in operative position, that I designed the tie forming the subject matter of this invention.

In the illustrated embodiment characterizing this invention there is shown a metallic tie 5 of hollow construction substantially inverted U-shaped in cross section. Mounted on the upper surface of the tie spaced from either end is a plate-like clip 6 having an upwardly deflected portion 7 adapted to overlie and engage the outer flange 8 of the transversely extending rail 9, which when secured to the tie 5 by bolts or other suitable fastening means 10 is adapted to grip the said flange 8 to hold the rail in place and prevent its lateral or longitudinal displacement.

An integral loop or strap-like member 11 is formed in the surface of the tie 5 slightly spaced from each of the inner flanges 12 by providing a pair of spaced parallel transverse cuts and raising or striking up the portion between such lines above the surface plane of the tie. The said loop 11 is adapted to receive a slidably movable clip 13 comprising an upwardly deflected flange engaging portion 14, the other or free end terminating in an upstanding operating member or lug 15. When the clip 13 is brought into operative engagement with the inner flange 12 of the rail 9, a wedging effect is obtained between the tie surface, the flange, and the loop 11, which in cooperation with clip 6 firmly secures the rail 9 against lateral or longitudinal displacement. An opening or aperture 16 is formed in the clip 13 adapted to selectively register with a series or plurality of apertures 17 formed in the loop member 11, so that the clip 13 may be locked in the desired adjusted position according to the particular size of the rail 9 by a locking pin 18 passing through such registering apertures. While for the expeditious laying of the track, I have preferably shown the locking means as a pin, a bolt or other suitable locking means may be employed if desired. And likewise, it will be understood that in order to increase the adjustability of clip 13 a plurality of apertures 16 may be formed therein if desired. However, the size of the rail and the range

of adjustment of clip 13 is such as not to materially affect the wheel gauge.

- A transverse rib or key-stop 19 is provided on the surface of the tie 5 spaced inwardly from each of the loops 11, formed by pressing upwardly portions of the upper wall of the tie, such ribs being adapted to limit the movement of clip 13 in flange disengaging direction to normally prevent complete separation of the same from the loop 11 and consequent loss during handling of the tie, but not sufficiently high to prevent the manual insertion of said clip in loop 11 or possible disengagement therefrom.
- 10 From the above it is apparent that I have designed a tie having novel rail attaching means and adapted to lend itself to expeditious track construction by being readily adjustable to different sized rails and quickly and easily secured to or detached therefrom, and capable of being manufactured from sheet metal at a minimum expenditure of time, labor and material.

Although in practice, I have found that the form of my invention illustrated in the accompanying drawings and referred to in the above description as the preferred embodiment is the most efficient and practical; yet realizing the conditions concurrent with the adoption of my device will necessarily vary, I desire to emphasize that various minor changes in details of construction,

proportion and arrangement of parts, may be resorted to within the scope of the appended claims without departing from or 35 sacrificing any of the principles of this invention.

Having thus described my invention, what I desire protected by Letters Patent is as set forth in the following claims:

- 40 1. A metallic railway tie having rail securing means mounted thereon, said means including a movable rail engaging means, an integral loop having a plurality of apertures formed therein and adapted to receive the movable means, said movable means having an aperture for selective registration with the apertures in the loop, and means extending through the registered apertures to lock the movable means in rail engaging 45 position.
2. A metallic railway tie having rail securing means mounted thereon, said means including a slidable rail engaging clip, an integral loop formed on the upper surface 55 of the tie in which the clip is slidably mounted, stop means formed on the surface of the tie to limit the retractile movement of the clip and prevent its complete separation from the loop, and means cooperating with the loop and clip to lock the latter in adjusted rail engaging position.

ADRIAN R. ROGERS.
